(57) **CLAIM**

The ornamental design for a display screen or portion thereof with animated graphical user interface as shown and described.

DESCRIPTION

FIG. 1 shows a first image in a sequence for display screen or portion thereof with animated graphical user interface showing our new design;

FIG. 2 shows a second image thereof;

FIG. 3 shows a third image thereof;

FIG. 4 shows a fourth image thereof;

FIG. 5 shows a fifth image thereof;

FIG. 6 shows a sixth image thereof;

FIG. 7 shows a seventh image thereof;

FIG. 8 shows an eighth image thereof;

FIG. 9 shows a ninth image thereof;

FIG. 10 shows a tenth image thereof;

FIG. 11 shows an eleventh image thereof;

FIG. 12 shows a twelfth image thereof;

FIG. 13 shows a thirteenth image thereof;

FIG. 14 shows a fourteenth image thereof;

FIG. 15 shows a fifteenth image thereof;

FIG. 16 shows a sixteenth image thereof;

FIG. 17 shows a seventeenth image thereof;

FIG. 18 shows an eighteenth image thereof;

FIG. 19 shows a nineteenth image thereof;

FIG. 20 shows a twentieth image thereof;

FIG. 21 shows a twenty-first image thereof;

FIG. 22 shows a twenty-second image thereof;

FIG. 23 shows a twenty-third image thereof;

FIG. 24 shows a twenty-fourth image thereof;

FIG. 25 shows a twenty-fifth image thereof;

FIG. 26 shows a twenty-sixth image thereof;

FIG. 27 shows a twenty-seventh image thereof;

FIG. 28 shows a twenty-eighth image thereof; and,

FIG. 29 shows a twenty-eighth image thereof.

The outer broken line rectangle shows the display screen or portion thereof and forms no part of the claimed design. In FIG. 23, the two long horizontal broken lines form part of the claimed design. The broken lines depicting a finger in FIGS. 2, 4, 6, 8, 10, 12, 14, 18, 20, 22, and 27 show environment and form no part of the claimed design. All other broken lines show portions of the animated graphical user interface and form no part of the claimed design.

The appearance of the display screen or portion thereof with animated graphical user interface transitions sequentially between the images shown in FIGS. 1-29. The process or period in which one image transitions to another forms no part of the claimed design.
